UNITED STATES PATENT OFFICE.

HOWARD S. F. BARNER, OF ALLENSTOWN, PENNSYLVANIA.

AIR-CLEANING MACHINE.

1,100,940.

Specification of Letters Patent. Patented June 23, 1914.

Application filed September 30, 1912. Serial No. 723,256.

To all whom it may concern:

Be it known that I, HOWARD S. F. BARNER, a citizen of the United States, residing at Allentown, in the county of Lehigh and State of Pennsylvania, have invented certain new and useful Improvements in Air-Cleaning Machines; and I do declare the following to be a full, clear, and exact description of the invention, such as will enable others skilled in the art to which it appertains to make and use the same.

This invention relates to means for extracting dirt and dust from air by forced draft, and more especially it is an improvement in the dust bag usually employed in a vacuum cleaner, and the parts coacting with said bag.

The object of the invention is to provide means for automatically and periodically emptying said bag of its contents, and discharging the same into a suitable receptacle.

Another object is to improve the construction of the suction and cleaning mechanism for drawing the dust-laden air into said bag and extracting the air from the dust within the bag and filtering it as it were so as to leave only the dust and dirt therein.

With these and other objects in view, the invention consists of certain novel features of construction and combination and arrangement of parts as will be more fully described and claimed.

In the accompanying drawings; Figure 1 is a central vertical longitudinal section through a street sweeping machine with my invention applied thereto. Fig. 2 is a vertical cross section taken on the line 2—2 of Fig. 1. Fig. 3 is a central longitudinal section of the air suction chamber of the machine. Fig. 4 is a vertical cross section of the same taken on a line 4—4 of Fig. 3. Fig. 5 is a similar view taken on the line 5—5 of Fig. 3.

The mechanism comprising the gist of the present invention may of course be applied in a number of ways and to a variety of machines; but in this specification I have described it as connected with the inner end of a dust-tube which forms part of a street cleaning machine, the other end of said tube having a suction head which picks up the dirt from the street or roadway contiguous to a brush. However, I do not wish to be confined to this strict application of the invention, as it is obvious that it could be used in other ways. In the drawings hereto at-

tached the street cleaning machine illustrated may be carried by any suitable form of truck and is here shown as being mounted on the frame 1 of a motor vehicle. The frame 1 is supported on front wheels 2 and rear wheels 3, said rear wheels being fixed on a driving axle 4 having sprocket gears 5 connected by sprocket chains 6, with sprocket pinions 7 fixed on a counter-shaft 8 mounted in suitable bearings on the frame 1 of the machine. On the frame 1 preferably at the forward end of the machine is arranged a suitable motor 9 having a drive shaft 10 that extends rearwardly and is connected at its rear end by suitable gears with the counter-shaft 8.

Revolubly mounted in suitable hangers 11 is a cylindrical brush 12 preferably disposed at a short distance from and in front of the rear wheels; and said brush is connected with the driving mechanism of the vehicle in any suitable manner so that it will be driven in the proper direction when the machine is propelled and may be thrown out of gear at the will of the operator.

In order to collect the dirt swept up by the brush 12, I provide a suitable suction head comprising a dustpan or tray 22, which is provided with a hood 23 and is connected with the lower end of a dirt conducting tube 24 which extends upwardly through the floor of the vehicle and has its upper end turned downwardly and connected with a dust-collecting receptacle or air-filtering bag 25. The bag 25 is arranged in an air suction cylinder 26 which is suitably supported in the body of the vehicle and to which midway between its ends is connected the upper end of the dirt-conducting tube 24, the bag 25 also being secured to this end of the tube 24 as hereinafter described. The bag 25 when thus arranged extends transversely through the cylinder 26 and has its opposite end connected with a discharge opening in the side of said cylinder. This opening is provided with a trap door 27 which is adapted to automatically open when the bag is filled with dirt and to automatically close after the dirt has been discharged from the bag. The dirt, when discharged from the bag through the opening in the cylinder, falls into the body 28 of the vehicle, which constitutes the receptacle provided to receive the same.

The cylinder 26 is divided by transverse partitions 29 into a central compartment

30 and end compartments or suction chambers 31. The partitions 29 are preferably convexed toward the central chamber 30 of the cylinder and are provided with a plurality of air holes 32, which are covered by a fine mesh wire netting and provided with outwardly opening check valves 32^a as shown. Suitable air outlets are also provided in the cylinder wall, opening from the end compartments 31 of the cylinder. Arranged in the suction chambers or compartments 31 are suction pistons 33 having piston rods 34 which project outwardly through the ends of the cylinder and are connected with operating levers 35. The levers 35 are pivotally secured at their lower ends to the frame or body of the vehicle adjacent to the opposite ends of the cylinder 26 and are connected at their upper ends by a connecting rod 36. The rod 36 is provided with a right angular arm 37 which is operatively connected by a pitman rod 38 to a crank disk 39 on the end of a piston operating shaft 40 which is mounted in suitable bearings on the frame of the machine. Loosely mounted on the opposite end of the shaft 40 is a beveled gear 41 which is engaged with and driven by a beveled gear 42 fixed on one end of a power transmitting shaft 43 which is mounted in suitable bearings beneath the body of the vehicle and is connected to the drive shaft 10 of the motor by beveled gears 44 and 45 as shown. The gear 41 is operatively connected to the shaft 40 by a clutch one member 46 of which is formed on or secured to the gear 41 and the other member 47 of which is slidably keyed to the shaft 40 and is adapted to be shifted into and out of engagement with the member 46 by a suitable clutch shifting lever. By thus constructing and arranging the air suction mechanism, it will be seen that when the clutch member 47 is thrown into engagement with the clutch member 46 of the gear 41, the pistons 33 will be operated in the suction chambers 31 of the cylinder 26 and will thus create a suction through the tube 24 and the suction head, thereby drawing the dirt up said tube and into the dust bag 25. The dust and dirt, when thus drawn into the bag 25, will be retained therein while the air is drawn and filtered through the sides of the bag and is discharged through the check valves of the cylinder. The trap door 27 is fastened in closed position by an automatically operated catch comprising a latch bolt 50 which is slidably mounted in a keeper 51 secured to the side of the cylinder adjacent to the lower edge of the door. The outer end of the bolt is beveled so that the same is pushed back by the edge of the door when swung to a closed position. As soon as the door is closed the bolt is again projected and engaged with the door by a suitable spring 52 as shown.

The door 27 is provided with a suitable spring hinge 53 whereby the same is swung to a closed position after being opened to discharge the contents of the filtering bag.

The latch bolt 50 is automatically retracted to release the door, by means of a bell crank lever 54 which is pivotally mounted on a suitable bracket on the inner side of the cylinder and has its shorter arm 55 projecting through a slot 56 in one side of the cylinder and loosely connected with the adjacent end of the latch bolt as shown. The longer arm 57 of the bell crank lever projects through a slit in the side of the filtering bag 25 near its outer end and on the arm 57 is formed a narrow plate 58 against which the dirt accumulating in the bag will press. By thus constructing and arranging the bolt releasing mechanism it will be seen that when the dirt has accumulated in the bag to exert sufficient pressure on the plate 58 of the bell crank lever and on the door, the bell crank lever will be rocked thus retracting the bolt against the tension of the spring 52. Said pressure will then open the door, thereby permitting the escape of the contents of the bag into the body of the vehicle which forms the receptacle for the dirt. After the dirt has been discharged in this manner the spring hinge 53 will swing the door back and together with the suction through the discharge opening in the cylinder will close the door. When thus closed the latch bolt will spring into engagement with the door and hold the same closed until the filtering bag is again filled.

While the pistons 33 in the suction chambers 31 of the cylinder 26 may be of any suitable construction the same are here shown and are preferably in the form of flexible partitions or diaphragms which are forced inwardly and outwardly by the piston rods 34 in the manner described.

From the foregoing description taken in connection with the accompanying drawings, the construction and operation of the invention will be readily understood without requiring a more extended explanation.

Various changes in the form, proportion and the minor details of construction may be resorted to without departing from the principle or sacrificing any of the advantages of the invention, as claimed.

Having thus described my invention, what I claim is:

1. The combination with a tube, and a door normally closing its outlet end; of a bolt engaging the free edge of said door when it is closed, a narrow plate extending across the interior of said tube near its outlet end, and connections between said plate and bolt for retracting the latter when said plate is moved by the pressure of accumulated material within the tube.

2. The combination with a receptacle, and a door normally closing its outlet end; of means for latching said door when it is closed, a plate within said receptacle near its outlet end, and operating connections between said plate and latching means for retracting the latter when said plate is moved by the pressure of accumulated material within said receptacle.
- 10 3. The combination with a tube, and a door hingedly connected therewith for closing its outlet end; of means for latching the door when closed, and a bell-crank lever pivotally supported and having one arm projecting across the interior thereof and adapted to be actuated by the pressure of material within said tube and the other arm connected with said latching means, for the purpose set forth.
- 15 4. The combination with a tube having a slot in one side near its outlet end, and a door hingedly connected with the other side of said tube at its outlet end; of a bell-crank lever having one arm projecting through

said slot and across the interior thereof and 25 adapted to be actuated by the pressure of accumulated material within said tube, and latching means for the free edge of the door, the other arm of said lever being connected with said means, for the purpose set forth.

5. The combination with a receptacle having an outlet at its lower end and a slot in one side near said outlet, a door adapted to close said outlet, and a spring hinge for closing the door; of a spring-actuated bolt for 35 engaging the free edge of the door, and a bell-crank lever pivotally supported at its angle and having one arm projecting through said slot into the interior of said receptacle and the other arm connected with 40 said latch.

In testimony whereof I have hereunto set my hand in presence of two subscribing witnesses.

HOWARD S. F. BARNER.
